UNITED STATES PATENT OFFICE.

ARTHUR O. JENNINGS, OF SOUTHPORT, CONNECTICUT.

DESIGN FOR A CLOCK-CASE.

SPECIFICATION forming part of Design No. 15,558, dated November 18, 1884.

Application filed September 10, 1884. Term of patent 7 years.

To all whom it may concern:

Be it known that I, ARTHUR O. JENNINGS, a resident of Southport, in the county of Fairfield and State of Connecticut, have invented and produced a new and original Design for a Clock-Case, of which the following is a full description, in connection with the accompanying photograph, which represents a face-view of my new design for a clock-case.

5 In the accompanying photograph, the letter A represents the body of my clock-case, the same being shaped to resemble a padlock, but having a dial, B, in its face. The body A has an ornamental attachment, C, in form of a chain, and has a base, D, in form of a key.

10 I claim—

1. The design for a clock-case, the same consisting of the body A and dial B, substantially as shown.
2. The design for a clock-case, the same consisting of the body A, dial B, and chain-shaped ornament C, substantially as shown.
3. The design for a clock-case, the same consisting of the body A, dial B, and key-shaped base D, substantially as shown.
4. The design for a clock-case, the same consisting of the body A, dial B, ornament C, and key-shaped base D, substantially as shown.

25 A. O. JENNINGS.
